UNITED STATES PATENT OFFICE

90,848

DESIGN FOR A STAND PEDESTAL

William E. Karl and John Vanderveen, Grand Rapids, Mich.

Application January 16, 1932. Serial No. 42,519

Term of patent 14 years

To all whom it may concern:

Be it known that we, WILLIAM E. KARL, a citizen of the United States, residing at 641 Giddings, S. E., Grand Rapids, in the county of Kent and State of Michigan, and JOHN VANDERVEEN, a citizen of the United States, residing at 831 Courtney, N. W., Grand Rapids, in the county of Kent and State of Michigan, have invented a new, original, and ornamental Design for a Stand Pedestal, of which the following is a specification, reference being had to the accompanying drawing, forming a part thereof, in which:—

The figure is a perspective view of the stand pedestal showing our new design.

We claim:

The ornamental design for a stand pedestal substantially as shown.

WILLIAM E. KARL.
JOHN VANDERVEEN.
